UNITED STATES PATENT OFFICE.

GEORGE F. ALBRECHT, OF WOONSOCKET, RHODE ISLAND, ASSIGNOR TO WOONSOCKET MACHINE & PRESS CO., INC., OF WOONSOCKET, RHODE ISLAND, A CORPORATION OF RHODE ISLAND.

WEIGHTING DEVICE FOR DRAWING FRAMES.

Application filed July 14, 1922. Serial No. 575,104.

To all whom it may concern:

Be it known that I, GEORGE F. ALBRECHT, a citizen of the United States, residing at Woonsocket, in the county of Providence, 5 State of Rhode Island, have invented a certain new and useful Improvement in Weighting Devices for Drawing Frames, of which the following is a specification, reference being had therein to the accompanying drawings.

The invention has relation to the weighting devices by means of which rolls of drawing frames are caused to press firmly against other rolls or other coacting elements upon 15 which they rest, to ensure proper cooperation in holding, feeding, and drawing the slivers of fibrous material passing through the sets of rolls.

More particularly, the invention relates to 20 the weight-hooks constituting elements of the said devices, and to the pieces connecting the weight-hooks with the rolls with which the weight-hooks, etc., are combined.

The general object of the invention is to 25 produce weighting devices of improved construction facilitating application, or removal and replacement, of the respective weight-hooks whenever necessary, with the weight-lifting bars in place in the machine; 30 and also to produce devices comprising simplified connections between a weight and the roll upon which it acts.

An illustrative embodiment of the invention is shown in the drawings, in which latter,—

Fig. 1 shows in vertical section certain portions of a drawing frame containing such embodiment.

Fig. 2 is an edge view of one of the weight hooks.

Referring to the drawings,—

The horizontal beam of the machine frame is indicated at 1, at 2 is one of the stands mounted on said beam, and at 3, 3, etc., are 45 roll-bearing blocks mounted upon said stands and each formed with a vertical slot receiving journals of a bottom roll 4 and a companion top-roll 5, a bearing 6 for the journal of the bottom roll being located at 50 the bottom of the said slot. As thus far referred to, the parts are as usual.

At 7, 7, etc., are so-called wire hooks which are hung upon the journals of the top-rolls 5; at 8, 8, etc., are so-called weight-hooks

which are hung to the hooked lower ends of 55 the wire hooks 7, 7, etc.; and at 9, 9, etc., are weights which are hung by means of their bails 91, 91, etc., to the hooks 83, 83, etc., formed upon the lower ends of the weight-hooks. The general relations, and 60 the effect of the weights in pressing the top-rolls down upon the bottom rolls, are as usual. At 10, 10, etc., are lifter-bars of 65 usual character extending transversely of the machine, and provided for service in 70 raising and supporting the weight-hooks and weights when it is desired to relieve the top-rolls of the effect of the weights. The mode of engagement of the lifter-bars with the weight-hooks is explained hereinafter. The 75 lifter-bars are shown as having combined therewith means for raising them, in the usual shape of a roll 11 mounted eccentrically in the machine frame under the lifter-bars, the shaft 12 of the said eccentric roll 80 being journalled in bearings at 13, 13, in front and rear brackets 17, 17, connected with the said frame, and the extended front end-portion of the said shaft being provided with a handle 14 by means of which the operator may turn the shaft and eccentric roll 85 to raise the lifter-bars, weight-hooks, and weights, to relieve the top-rolls from the action of the weights, as aforesaid; or to lower the lifter-bars, etc., to permit the 90 weights to exert their effect upon the rolls again. As will be understood, the eccentric roll, etc., are duplicated at opposite sides of the machine, to enable the action in raising the lifter-bars to be applied at both ends of 95 the said bars. At 15 is the usual retaining rod, extending loosely in the direction from front to rear through holes in the series of lifter-bars, and having its ends entered into vertical guideways 16, 16, in the brackets 17, 17. The retaining rod moves up and down in the said guideways as the lifter-bars are raised and lowered through rotation of the pair of eccentric rolls 11, and serves to prevent endwise shift of the lifter-bars.

In usual practice heretofore, the weight-hooks employed in drawing frames have been made, with closed slots to receive the lifter-bars. A drawback in connection with this construction is that, in assembling the 105 parts of a drawing frame, the weight-hooks must all be introduced into place before the lifter-bars are put into their places;

2
in disassembling the parts, the lifter-bars must first be removed. This has its inconvenience in case a weight-hook should become broken, which happens occasionally 5 through accident or through carelessness in applying a weight thereto, as in the process of assembling or in replacing the weight after removal thereof for some purpose. In order to effect the removal of a broken 10 weight-hook having a closed loop and the insertion of a new one, it is necessary first to withdraw from the machine the lifter-bar passing through the slots of the row of weight-hooks containing the broken 15 weight-hook, and after the broken weight-hook has been replaced by a new one replace the lifter-bar. In effecting such replacement the lifter-bar has to be threaded through the slots of all the weight-hooks of 20 such row in order to assemble the parts for further operation.

In accordance with the invention, and in order to facilitate the insertion of weight-hooks into their proper working relations 25 in a drawing frame while the lifter-bars 10, 10, etc., are in place in the machine, and likewise in order to provide for removal of a broken weight-hook and insertion of a new one without withdrawal of 30 the corresponding lifter-bar from its place, I form each weight-hook with an open notch to loosely fit the top of the lifter-bar with which it is associated in use. The weight-hook is provided at one side of the said 35 notch with an outstanding downwardly pointing finger 101, and with a shoulder 102 between such finger and the lower portion 103 of the body of the hook. The shoulder is adapted to be engaged by the 40 lifter-bar with which the weight-hook is associated in use, when such lifter-bar is raised, so that the lifter-bar shall raise the weight-hook with it. The downwardly pointing finger 101 extends alongside the 45 lifter-bar so as to prevent relative displacement of the weight-hook and lifter-bar with relation to each other. This construction enables a weight-hook to be placed in the drawing frame and placed in proper working 50 relations with a lifter-bar already in the machine, and also enables a weight-hook to be removed without it being necessary to withdraw the lifter-bar first. Substitution of a fresh weight-hook in case of 55 breakage of one already in the drawing frame is facilitated.

It is customary to employ intermediate parts, usually termed stirrups, between the wire hooks 7, 7, etc., and the weight-hooks 60 8, 8, etc. Such stirrups serve to connect the weight-hooks in a flexible manner with the wire hooks. In accordance with the invention I dispense with stirrups, thereby reducing materially the number of separate parts, 65 and I extend the upper ends of the weight-

hooks upward in the form of elongated stems, 81, 81, etc., and I engage the upper ends of the said stems directly with the lower ends of the wire hooks. The stems 81, 81, etc., work freely in holes through the 70 horizontal web-portion of the beam 1 of the machine frame.

For the engagement of the upper ends of the stems 81, 81, etc., of the weight-hooks with the lower ends of the wire hooks 7, 7, etc., I form the upper end of a weight-hook stem 81 with an elongated slot 82, Fig. 2. The hook 71 at the lower end of a wire hook 7 is engaged in this slot, and the upper end-wall of the slot rests in the bend 80 of the said hooked lower end. One purpose in view in forming the upper end of the weight-hook stem with a vertically elongated slot, instead of with a round or other hole in which the wire hook closely fits, is 85 to facilitate the operation of engaging the weight-hook and wire hook with each other in the process of assembling the parts in the machine, and also facilitate the operation of disengaging the parts from each 90 other. Another is to avoid cramping engagement between the hooked lower end of the wire hook and the edge of the opening through the weight-hook stem.

If the weight-hook stem were made with 95 a small hole closely fitting the wire hook, it would be difficult to insert the hooked lower end of the wire hook into the hole after placing the parts in approximate position within the machine-frame, especially in case the free extremity of the said hooked lower end should be caused to project upward to the extent indicated in Fig. 1. This extent of upward projection is desired in order to safeguard against accidental disconnection 100 of the weight-hook and wire hook from each other when the weight-hook and weight have been raised by means of the lifter-means.

When a weight-hook is raised by upward movement of the lifter-bar with which it is associated, swaying movement of its upper end and of the hooked lower end of the wire hook occurs. In the case of a hole in the upper end of the weight-hook closely fitting 110 the hooked portion of the wire hook, such swaying would cause locking or cramping of such lower end in the hole. This would cause inconvenience in disengaging the weight-hook from the wire hook. Moreover, it would be difficult to disengage the weight-hook from the wire hook, in case the former had a small hole, and the lower end of the wire hook were upturned to the extent shown in Fig. 1 of the drawings. The 115 usual conditions existing in the case of a drawing frame would necessitate the cooperation of two men in assembling or disassembling the parts in the machine. By having an elongated slot 82 in the upper end 120 13

of the weight-hook stem, the parts can be placed in working relations readily. They can be as readily disengaged from each other, because for the purpose of disengaging them it is necessary merely to raise the weight-hook vertically until the upper end-wall of slot 82 is above the point of the hook 71 and then swing the weight-hook until its stem has been carried out clear of the 10 said point.

Removal of a weight-hook is accomplished, after preliminary raising of the series of lifter-bars and the assemblage of weight-hooks by means of the eccentric 15 lifter-rolls. When the weight-hooks have been raised, the particular weight-hook which it is desired to remove may have its upper end disengaged from the corresponding wire hook by swinging such upper end 20 out of engagement with the hooked lower end of the said wire hook. Assuming the corresponding weight to have been detached from the lower end of the weight-hook, the 25 open notch of the weight-hook may be lifted off from the lifter-bar, and the weight-hook drawn out of the machine. The insertion of a weight-hook in the place of the one removed may likewise be effected in obvious manner with facility.

30 What is claimed as the invention is,—

1. In a drawing frame, the combination with drawing rolls, hooks suspended from

the journals of the said rolls, weights, and weight-lifting bars, of weight-hooks each having an integral stem detachably engaging by its upper end with one of the hooks first mentioned, and also an open notch to fit removably over the corresponding lifting bar. 35

2. In a drawing frame, the combination 40 with drawing rolls, hooks suspended from the journals of the said rolls, weights, and weight-lifting bars, of weight-hooks each having an upwardly extending integral stem having a vertically elongated slot occupied 45 by the hooked lower end of one of the hooks first mentioned, and the lower portion of the hook having an open notch to fit removably over the corresponding lifting bar.

3. In a drawing frame, the combination 50 with drawing rolls, weights, and weight-lifting bars, of weight-hooks having open notches which removably fit the said bars, upwardly extended integral stems having elongated slots in their upper portions, and 55 wire hooks having their hooked lower ends engaged in the said slots and their hooked upper ends engaging with the roll journals.

In testimony whereof I affix my signature in presence of two witnesses.

GEORGE F. ALBRECHT.
